UNITED STATES PATENT OFFICE.

ALBERT H. DE VOE, OF WESTFIELD, NEW JERSEY, ASSIGNOR TO THE SINGER
MANUFACTURING COMPANY, A CORPORATION OF NEW JERSEY.

FEEDING MECHANISM FOR SEWING-MACHINES.

1,300,358.

Specification of Letters Patent.

Patented Apr. 15, 1919.

Application filed June 3, 1914. Serial No. 842,595.

To all whom it may concern:

Be it known that I, ALBERT H. DE VOE, a citizen of the United States, residing at Westfield, in the county of Union and State 5 of New Jersey, have invented certain new and useful Improvements in Feeding Mechanisms for Sewing-Machines, of which the following is a specification, reference being had therein to the accompanying drawings.

10 This invention relates to feeding mechanism for that class of sewing machines adapted more especially for stitching heavy, or stiff goods such as canvas and the like, which employ auxiliary feeding mechanism 15 to aid the main feed-dog to properly advance the work through the machine.

In the present construction the machine is provided with the usual reciprocating needle and coöperating loop-taker mechanism, 20 actuated from a main-shaft mounted in bearing-supports rising from the bed-plate below the usual overhanging arm. The main feed-bar is pivotally connected to and projects forwardly of a feed-rocker, and at its 25 forward end is supported by the strap of a lifting eccentric on the main-shaft. To the feed-rocker is connected one end of a pitman provided at its opposite end with a strap embracing a second eccentric on the 30 main-shaft, which serves to impart operative movements to the feed-rocker and hence feeding movements to the main feed-bar which receives rising and falling movements from the first named eccentric.

35 Supported above the bed-plate at the rear of the main feed-dog by a suitable sustaining member is a vertically-movable spring-pressed feed-roller which coöperates with an arcuately movable, rising and falling, auxiliary feed-dog. The auxiliary feed-dog is 40 formed with a serrated curved surface to correspond with the surface of the feed-roller, and is provided with a sliding post which fits within the bearing sleeve of a 45 rocking carrier journaled within suitable bearing supports at the rear of the main feed-dog. The auxiliary feed-dog carrier is given its rocking movements by means of an adjustable link connection with the feed- 50 rocker which actuates the main feed-bar, so that simultaneous feeding movements are imparted to both the main and auxiliary feed-dogs from a common actuating member. The connection between the main- 55 shaft and the feed-rocker permits a change

in the throw of both feed-dogs by one adjustment; and the connection between said rocker and the auxiliary dog is such as to permit an independent adjustment of the latter to change the length of its throw relatively to the main feed-dog.

The means for imparting rising and falling movements to the auxiliary feed-dog comprise an elbow-lever pivotally mounted upon a block clamped upon the bearing sleeve of the carrier which receives the sliding post of the auxiliary feed-dog. A link connects one arm of the elbow-lever with the auxiliary feed-dog, and to the second arm of the elbow-lever is connected, either directly or through certain instrumentalities, the rearwardly extending end of a pitman which receives reciprocatory movements from a third eccentric on the main-shaft.

70 The construction above set forth provides 75 a positively driven auxiliary feeding member which is so connected with the actuating mechanism for the main feed-dog that its feeding movements are simultaneous with the latter and of the same length, or of a 80 greater or less length, as desired.

In the drawings, Figure 1 is a perspective view of the improvements applied to a Singer sewing machine of a type in which the main-shaft is journaled in bearing supports rising from the bed-plate below the overhanging arm, the machine being shown in dotted lines. Fig. 2 is a side elevation, partly in section, of the main and auxiliary feeding members and the operative connections between the same and the main-shaft of the sewing machine. Fig. 3 is a perspective view of the rocking carrier for the auxiliary feed-dog; and Fig. 4 is a perspective view of the auxiliary feed-dog, the elbow-lever which imparts rising and falling movements thereto, and certain connecting elements. Fig. 5 is a perspective view of a sewing machine provided with a modified form of the improvements. Fig. 6 is a perspective view of certain elements of the auxiliary feed-lift, as employed in the modified form of the improvements. Fig. 7 is a perspective view of the throat-plate, and Fig. 8 is a similar view of the presser-roller and connected parts employed in the modified form of the improvements.

100 As represented in the drawings, the invention is shown in connection with a sewing machine constructed with the bed-plate 105 110

A, standard B, and overhanging arm C in which is journaled the needle-actuating shaft 1, the latter being operatively connected with the usual reciprocating needle-bar 2 carrying needle 3.

The needle-actuating shaft 1 receives operative movements through connections with the main-shaft 4 which is journaled in suitable bearings within the standard B and a bearing support 5 rising from the bed-plate A. The main-shaft carries at its end the usual balance-wheel 6 and is provided with a feed-lifting eccentric 7 which is embraced by the strap 8 of a short pitman 9, provided at its end with an aperture to receive a pivotal stud 10 which passes through a similar aperture formed in feed-bar 11, the latter being formed with a vertical channel to receive the supporting post 12 of the main feed-dog 13, which is held in position by means of a fastening screw 14.

The enlarged rearwardly extending end of the feed-bar 11 is formed with a transverse aperture to receive a pivotal stud 15 supported within the bearing bosses 16^x of the yoke-arm 16 forming part of a feed-rocker comprising the arms 16, 17, 18 projecting from the hollow rock-shaft 19 pivotally supported at each end by means of suitable center screws fitted within bearing bosses on the bed-plate A. One of said center screws is indicated by the numeral 20 in Fig. 1, a cupped bearing disk 21 being interposed between said screw and the hollow rock-shaft, said disk being suitably clamped within the latter.

The upwardly extending arm 17 of the feed-rocker is formed with a segmental slot 23 to receive a stud-screw 24 fitted within the enlarged end of rearwardly extending pitman 25, the latter being provided with a strap 26 which embraces the feed-actuating eccentric 27 on the main-shaft 4. The form of arm 17 permits the adjustment of pitman 25 toward and from the axis of the feed-rocker to vary the length of feeding movements, and the pitman is clamped in its adjusted position by means of the clamping nut 24^x and a washer 28 surrounding the stud-screw 24 adjacent arm 17.

Rising from the bed-plate at the rear of the main feed-dog 13 are two supporting arms D and E, the latter being provided with a substantially U-shaped extension E^x which is adapted to sustain a presser-roller for use in conjunction with an auxiliary feeding-member, as hereinafter more fully described. Fitted within suitable bearings supported by the members D and E are the fulcrum-pins 29 of a carrier-block 30 formed with a vertical aperture within which is fitted a bearing sleeve 31 which receives the sliding-post 32 of auxiliary feed-dog 33, the under face of the dog being formed with a depression or annular recess to receive the slightly

enlarged head of the post, and the two members being secured together by means of a screw 34. Upon one fulcrum-pin 29 of the rocking carrier is fitted the enlarged apertured and split end 35^x of a crank-arm 35, 70 said arm being clamped upon the pin by means of a screw 36^x. In the opposite end of the arm 35 is similarly clamped a stud-screw 37 which passes through one end of a link-bar 38, the opposite end of said link-bar being connected to arm 18 of the feed-rocker. It will be seen that the link-bar may be adjusted toward and from the axis of the feed-rocker to vary the movement of the rocking-carrier 31 and thus the throw of 80 the auxiliary feed-dog 33, such adjustment being effected by loosening the nut 40 on stud-screw 39 to permit said screw to be moved within the slot 41 of the arm 18.

An elbow-lever 42 is employed to impart 85 rising and falling movements to the auxiliary feed-dog 33. The said elbow-lever is provided with a boss 42^x which fits upon a stud 43 projecting laterally from a split and apertured block 44 clamped upon the bearing-sleeve 31 of the rocking-carrier 30. One end of the elbow-lever is apertured to receive a stud-screw 45 which is held in position by means of nut 46. The projecting end of stud 45 fits within the lower transverse boss 46^x of a link 47, the upper similarly formed boss of which fits between the apertured lugs 48 of the auxiliary feed-dog 33, a pin 49 being employed to pivotally connect said link and the dog, the pin being held in position by means of clamping screws 50.

It will be seen that the actuation of elbow-lever 42 will impart vertical reciprocating or rising and falling movements to the feed-dog, during which movements the post 32 will slide within the bearing sleeve 31 of carrier 30. The auxiliary dog rises immediately after the carrier 30 moves the same to its forward position prior to a feeding movement; and at the termination of the feeding movement said feed-dog is lowered by the reverse movement of the elbow-lever 42. The elbow-lever is operated by means of a pitman connection with an eccentric on the main-shaft, the rear end of the pitman 51 being apertured to receive a stud 52 on one arm of the elbow-lever, and the forwardly projecting T-shaped end 51^x of the pitman fits upon, and is provided with a strap 53, 120 which embraces the eccentric 54, said strap being held in position by means of screws 55. The block 30 is cut away adjacent the bearing sleeve 31 to form a recess to receive and permit movement of the elbow-lever 125 and that end of the pitman 51 connected thereto.

A vertically movable presser-roller is employed in conjunction with the auxiliary feed-dog. As hereinbefore stated, the 130

presser-roller is sustained by the extension E^x of bearing support E , said extension being provided at its upper end with parallel vertical bearing bosses 56 and 57. The toothed 5 presser-roller 58 is mounted on a horizontal stud 59 supported by the downwardly extending arms 60 x of a bracket 60 provided on its upper face with the supporting pin 61 which fits loosely within boss 56 of the extension E^x . The bracket also carries a guide-pin 62 which slides within boss 57 of said extension. The pin 61 is provided with an adjustable stop-ring 63 which abuts the upper face of boss 56 and limits the downward 10 movement of the feed-roller, being held in its adjusted position by means of a clamping-screw 64. Intermediate the lower face of boss 57 and the upper face of bracket 60 and surrounding the guide-pin 62 is a coiled 15 spring 65 which acts to press the feed-roller downwardly into engagement with the fabric. The upper portion of the coiled spring 65 is engaged by the lower end of a hollow thumb-screw 66 movable within boss 20 57 and serving as a bearing for the guide-pin. It will be seen that manipulation of thumb-screw 66 will change the tension of spring 65 and hence the pressure of the feed-roller upon the fabric. 25 A lifting lever is employed to raise the feed-roller against the action of its spring, and for this purpose the extension E^x is provided with a transverse boss 67 adapted to receive a short rock-bar 68 which projects 30 from each face of the extension sufficiently to permit hand-operated lifting-lever 69 and a treadle-operated arm 70 to be clamped thereto. The lever 69 is provided with a nose 69 x which lies under a roller 71 on the 35 feed-roller supporting bracket 60. It will be seen that the bracket 60 and the feed-roller supported thereby may be elevated by hand pressure upon lever 69 or by actuation of the arm 70 through the intermediary of 40 a suitable treadle device, as desired. 45 A modified form of the improvements is illustrated in Figs. 5 to 8 of the drawings to adapt the same to a Singer machine of a type different from that shown in Fig. 1. 50 In the modification, the feed-rocker comprises the member 72 mounted upon a shaft 73 fitted within bearings afforded by the bearing supports F and G rising from the bed-plate of the machine, and having the 55 depending arm 74 connected by means of pitman 75 and strap 75 x with the adjustable feed-actuating eccentric 76 on the main-shaft 4. The enlarged rearwardly extending end 60 of the feed-bar 77 is mounted upon a pivotal stud supported within the bosses 72 x on the feed-rocker. At its forward end the feed-bar is provided with a yoke 78 which embraces a block 79 mounted upon the feed-65 lift eccentric on the main-shaft, whereby

rising and falling movements are imparted to the main feed-dog 80. The construction of the auxiliary feed-dog 33, the rocking carrier 30 therefor, and the elbow-lever 42 which serves to transmit rising and falling movements to the auxiliary dog, is the same in both forms of the improvements. The feed-rocker 72 is operatively connected to the carrier 30 by means of a link-bar 81 secured at one end by means of stud screw 81 x 75 to the depending arm 82 of the rocker and at its opposite end to a slotted crank-arm 83 clamped upon one of the carrier fulcrum-pins 29. The connection between the feed-rocker and the carrier 30 is an adjustable 80 one to permit changes in the feeding movements of the auxiliary feed-dog relatively to the main feed-dog and the adjustable feed-actuating eccentric 76 permits regulation of the stitch length by simultaneously 85 changing the effective movements of each feed-dog. 90 The elements employed to raise and lower the auxiliary feed-dog are the same as those illustrated in Figs. 1-4 of the drawings, 95 with the exception that a rocker and link are interposed between the elbow-lever 42 and the actuating pitman 51. The rocker in question comprises the rock-shaft 84 mounted within the bearing support F and having clamped 95 thereon at one end the slotted arm 85 which receives the stud-screw 86 of the pitman 51. Upon the opposite end of rock-shaft 84 is secured the upwardly extending arm 87 which carries a stud-screw 88 fitted within 100 the enlarged apertured end of a short link 89 having its opposite end fitted upon the stud 52 of elbow-lever 42. It will be seen that pitman 51 will rock arm 87 and, through the link connection with elbow-lever 42, will 105 alternately raise and lower link 47 and the auxiliary dog 33 connected therewith; and it will also be seen that the adjustable connection between pitman 51 and rock-arm 85 will permit changes in the height of movement of the auxiliary dog to correspond with 110 changes in the thickness of the material being acted upon. 115 The presser-roller 58 employed in the modification is constructed similar to that illustrated in Fig. 1 of the drawings. In the modification, however, the presser-roller is sustained by a forked extension 90 x of the lifting lever 90, and the latter is provided with a transverse bearing stud 91 which fits 120 within the bearing bosses 92 of a bracket 93 secured upon the head of the overhanging arm C . A coiled spring 94 having one end fitted within a socket formed in the head of the machine and its opposite end fitted 125 within a socket formed in the inner face of lifting lever 90 tends to press the presser-roller downwardly into engagement with the material. To accommodate materials of different thicknesses, and to prevent the pres- 130

sure of the feed-roller upon the teeth of the auxiliary feed-dog when the material is removed from the machine a detent-member 95 is provided to engage a pin 96 projecting 5 from the face of the lifting lever 90 whereby the feed-roller may be held slightly above the toothed face of the auxiliary feed-dog. The detent-member may be moved endwise to vary the distance between the presser- 10 roller and the auxiliary feed-dog, a clamping screw 99 serving to hold the detent-member in its adjusted position. The presser-roller may be elevated by pressure upon a hand piece h extending from the 15 lifting lever 90 above the head of overhanging arm C.

In Fig. 8 of the drawings, a treadle-operated device is illustrated whereby the presser-roller may be elevated by foot-pressure simultaneously with the elevation of the presser-foot (not shown). Supported by two brackets 98 and 98^x secured upon the overhanging arm C, is a rock-shaft 99, operated through treadle connections with 25 chain 100 and rock-arm 101 to simultaneously raise its connected arm 102 and swing inwardly its arm 103, whereby the link-bar 104 connected intermediate arm 102 and a collar 105 on presser-bar p is lifted to elevate the presser-foot, and a link 106 connected intermediate projecting pin 96 of the lifting-lever 90 and arm 103 is moved endwise to rock the lifting-lever and thereby elevate the presser-roller 58.

35 Upon the horizontal seats F^x and G^x afforded by the bearing supports F and G is secured a work-plate section 107 partially cut away intermediate its ends and formed with seats to receive the throat-plate 108. 40 The throat-plate 108 is provided with cross-bars 108^x spaced to correspond with the grooves formed in the auxiliary feed-dog and presser-roller, said cross-bars being formed with concaved lower faces so that 45 the grooves in the auxiliary dog may be made as shallow as possible without affecting the normal rise of the dog to work engaging position. The cross-bars 108^x in the throat-plate possesses a function not present 50 in the usual sewing machine throat-plate. This function is to counteract the tendency of the arcuately-movable auxiliary feed-dog to pull the material downward in a plane intersecting the work-plate, as the feeding 55 progresses.

It will be understood that the invention is susceptible of various changes in the form and arrangement of the coöperating elements, in addition to those of the modification 60 above described, and that the same is not limited to the precise embodiments herein illustrated.

Having thus set forth the nature of the invention, what I claim herein is:—

65 1. In a puller feeding mechanism for sew-

ing machines having a needle, the combination with a main feed-dog adjacent the needle and an auxiliary feed-dog located remote from and in rear of the needle, of an actuating rocker common to both dogs and 70 adapted to impart simultaneous feeding movements thereto, means for changing the length of feed of both dogs simultaneously, and means for changing the length of feed of the auxiliary dog independently of the 75 main dog.

2. In feeding mechanism for sewing machines, the combination with an actuating shaft and a feed-dog movable only in a vertical plane, of a rocking support and a fixed 80 fulcrum for said feed-dog means operatively connected with said shaft for actuating said support to impart feeding movements to the feed-dog and additional means adjustable upon the support and operatively 85 connected with said shaft for moving the feed-dog relatively to the support and into and out of feeding position.

3. In feeding mechanism for sewing machines, the combination with an actuating 90 shaft, of a main feed-dog and lifting means therefor on said shaft, a feed-rocker actuated by said shaft, a rocking support operatively connected to said feed-rocker, an auxiliary feed-dog mounted on said support 95 for movement relatively thereto, means including a lever fulcrumed upon said rocking support and operatively connected with the said actuating shaft for effecting rising and falling movements to the auxiliary 100 feed-dog, and a connection between said feed-rocker and the main feed-dog.

4. In feeding mechanism for sewing machines, the combination with an actuating shaft, of a feed-rocker and operative connections between the same and said actuating shaft, a rocking support provided with a bearing sleeve, a feed-dog provided with a post adapted to slide within said bearing sleeve, an elbow-lever movable upon said 110 rocking support, a connection between said elbow-lever and the feed-dog, a link connection between the feed-rocker and said rocking support and adjustable independently of the latter, and actuating means for 115 said elbow-lever.

5. In feeding mechanism for sewing machines, the combination with a feed-dog and a post upon which the feed-dog is mounted, of a rock-bar provided with a bearing-sleeve 120 adapted to receive the post of the feed-dog, a block adjustably secured to said sleeve and carrying a fulcrum stud, an elbow-lever mounted upon said stud, a link connection between the feed-dog and said elbow-lever, 125 an actuating shaft, actuating means connecting said shaft with the rock-bar, and means acting independently of the rock-bar for actuating the elbow-lever.

6. In feeding mechanism for sewing ma- 130

- chines, the combination with an actuating shaft and a feed-rocker operatively connected thereto, of a main feed-dog connected to said feed-rocker, a rocking support, an auxiliary feed-dog mounted upon said rocking support, means for raising and lowering the auxiliary feed-dog relatively to its rocking support, an operative connection between the feed-rocker and said rocking support, means for changing the length of movement of both feed-dogs simultaneously, and means for changing the length of movement of the auxiliary feed-dog relatively to the main feed-dog.
7. A sewing machine having a main work advancing mechanism including a feed-dog and a coöperating presser-foot in combination with puller feeding mechanism including an arcuately movable feed-dog and a co-operating presser-member in rear of and spaced from the primary work advancing mechanism, common means for imparting feeding movements to said dogs independent means for imparting lifting movements to said dogs, and means for changing the feeding movements of the puller feed dog without varying the action of the main dog.
8. In feeding mechanism for sewing machines, the combination with spaced main and auxiliary feed-dogs and a feed-rocker intermediate the same, of an actuating shaft provided with a feed-lift eccentric for the main dog, an operative connection between said shaft and the feed-rocker, an adjustable link connection between the feed-rocker and the main dog, a second rocker on which the auxiliary dog is slidably mounted for endwise movement, a feed-lift lever carried by said second rocker and connected with the auxiliary dog, an adjustable connection between the feed-rocker and the second rocker, and an operative connection between the shaft and the feed-lift lever.
9. In a puller feeding mechanism for sewing machines having stitch-forming mechanism including a needle, the combination with a main feed-dog having a feeding surface extending rearwardly of the needle throughout the stroke of the feed-dog, of a supplemental feed-dog operating in the rear of and spaced from the main dog, a main-shaft, independent eccentrics on the main-shaft for imparting lifting movements to both dogs and a single eccentric also on the main-shaft for simultaneously imparting feeding movements to both dogs.

In testimony whereof, I have signed my name to this specification, in the presence of two subscribing witnesses.

ALBERT H. DE VOE.
